[57] CLAIM

The ornamental design for a computer display with a computer generated icon, as shown and described.

DESCRIPTION

FIG. 1 is a front view of a computer display with a computer generated icon;

FIG. 2 is a front view thereof, on an enlarged scale;

FIG. 3 is a second embodiment thereof; and,

FIG. 4 is a front view of the second embodiment shown in FIG. 3, on an enlarged scale.

The computer display in all figure views is understood to be the exact surface on which the computer generated icon is displayed.
